SELF PROPELLED SLED

Filed March 22, 1928

CHARLES SCHUBERT Inventor

Attorney
Clarence S. Ashley

UNITED STATES PATENT OFFICE

CHARLES SCHUBERT, OF LONG ISLAND CITY, NEW YORK

SELF-PROPELLED SLED

Application filed March 22, 1928. Serial No. 263,660.

The invention relates to improvements in self propelled sleds and has particular reference to the general type of toy sleigh provided with a supporting body and runners having disposed thereon mechanism adapted to propel the same and its rider over ground, ice and snow surfaces, said propelling means being actuated by hand and foot power to effect the gliding movement of the structure. The object of the invention resides in the providing of suitable mechanism of an economical and durable character disposed upon the super-structure of the sleigh, beneath the supporting platform thereof connected with a hand and foot pedal actuating means for causing a gripping shoe propelling means to engage the surface upon which it rests to project the same forwardly by reason of a reciprocal action of said shoe, and propelling means, and of means controlled by said hand and foot-pedal actuating means for freeing such mechanism from the surface upon which it rides to return same automatically to the point of its engagement with the gliding surface to continuously project or drive the sled in the desired direction. Another object of the invention exists in the adaptation of the surface gripping propelling means as a brake mechanism during the moment of using the sled for coasting or gliding purposes since it is apparent that said propelling shoe may be so actuated by the hand lever and foot pedals as to permit same to engage the riding surface and held in contact therewith to form a positive braking means for use at moments of danger or possible injury to the rider of the device.

In the following I describe the general embodiment of the invention, the features thereof being more particularly defined hereinafter in the claims.

Fig. 1 is a side elevation of the sled; Fig. 2 is a plan view (parts being broken away) of said sled; Fig. 3 is a detail side elevation of the propelling mechanism of the sled; Fig. 4 is a detail side elevation showing said propelling mechanism in the forward stroke of said mechanism; and Fig. 5 is a cross sectional view of the sled on the line 5—5 of Fig. 1 of the drawings.

Similar numerals of reference indicate similar parts throughout the several views of the drawings.

In the drawings 1 designates a sled of the hand or toy type provided with a supporting body or platform 2, having disposed thereon by means of supporting brackets the usual form of steel runners 3. Runners 3, at the front end of the sled are held rigid at that point by means of cross head or strap 4.

Platform or body board 2, has depending therefrom by means of swinging yokes 5, mounted in brackets 6, a guide table 7, open at its bottom and provided with side channels 8, arranged to receive with sliding relation thereto the supporting plate 9, of propeller and brake shoe 10. The shoe 10, consists of two depending blades 11, having mounted on their lower edges friction straps 12, of rubber or any other suitable material and the supporting plate 9, has mounted therein rollers 13, pivotally supported at 15 therein and arranged to engage and roll upon the under surface 14, of the swinging table 7, and said blades 11, have mounted therein on their respective outer surfaces supporting pins 15^a arranged to receive portions of the mechanism the object of which is hereinafter described. Swinging table 7, is fulcrumed on yokes 5, in brackets 6 through which it may swing forwardly and laterally or in a reciprocal action by reason of the propelling actuating mechanism controlled by reason of the hand and foot movement of the projecting or propelling mechanism.

The reciprocal movement of table 7, is controlled through the functioning of foot pedals 16, pivotally mounted on hinged rockers 17, fastened to cross head 4, of sled 1, and having mounted on their lower ends or heel portions thereof, stay rings 18, receiving one end of each of the thrust rods 19, the opposite ends of which are pivotally fastened to yoke 20, mounted in brackets 21, on the under side of sled body 2. Said yoke 20, has disposed on its lower arm portion thereof rollers 22, engaging the upper surface of table 7, which latter surface has fastened thereon a stop 23, to limit the forward swing of said table 7, and to also provide an assisting means of return-

ing said carriage or table 7, to its forward position or the beginning of the projecting stroke of the propelling mechanism, as well as providing the means of moving said table in a forward and lateral as well as vertical up and down movement to bring the propelling and brake shoe 10, into engagement with the surface upon which the structure rides, all of said action being controlled and actuated by said foot pedals 16. A compression spring 24, has one of its ends attached to table 7, the other end being fastened to a bracket 25, mounted on the under side of platform 2, of sled 1.

15 A projecting strut 26, of body 2, of sled 1, has mounted therein on pin 27, an operating or propelling arm or lever 28, provided at its upper end with hand piece 29 and having mounted in its lower end beneath body 2, 20 a shaft 30, that receives the ends 31, of primary levers 32, the opposite ends of which are pivoted to the short ends of levers 33, mounted on stay bolt 34, supported on bracket 35 fastened to the said under side of body 25, the other or longer leverage ends 36, of said levers 33 carrying the ends of draw rods 37, the lateral ends of which are fastened to or attached upon pins 15^a on the side blades 11, of propelling and brake shoe 10, all of the 30 latter mechanism and that of the projecting structure of the device being controlled by the forward and backward rocking manipulation of the hand lever 28.

The operation of the structure is as follows:

35 The operator seated upon the sled body 2, places his feet upon foot pedals 16, grasps hand lever 28 and by rocking said pedals 16 with the ball portions of his feet, draws swinging table 7 forwardly in a semi-lifting movement, and simultaneously thrusts lever 28 forwardly which causes brake shoe and propeller shoe to roll forwardly within channels 8, of table 7, and by the depressing movement of the heel on pedal 16, causes the said 40 propeller shoe 10, to move downwardly until the friction straps 12, engage the surface upon which said sled operates, and then by reason of the lateral or backward pull of the operator on said hand lever 28, impel the structure in a forward projected manner. The repeated functioning of the device in the manner as described together with the tilting of the foot pedals 16, by the toe portion of 45 the foot of the operator which latter resets all of the actuating mechanism, produces a continued self propelled sled, and at the same time provides a brake mechanism for such a structure, since if the operator brings the shoe 50 10, forwardly and holds both foot pedals, 16, and lever 28, rigidly at a point wherein said shoe contacts the riding surface provides a positive brake mechanism for the device, thusly providing a sled of the self 55 propelled type and one that may be used as

a coaster having factors of safety not found in present day articles of a similar nature.

The device may be altered and changed in many ways and particularly in its mode of operation and means of actuating same, without departing generally from the natural scope of the invention.

What I claim and desire to secure by Letters Patent of the United States, is:

1. A device of the character described comprising a sled supporting structure, a swinging carriage disposed beneath said structure, foot controlled means for actuating said swinging table means controlling the limit of movement of said carriage, spring controlled means for assisting the movement of said carriage, a single propeller shoe mounted in and slideable with relation to said swinging carriage, hand controlled means for actuating said propelling shoe, means arranged to thrust said propelling shoe into contact with the riding surface of said sled by reason of the forward movement of said swinging carriage, means for actuating said propelling shoe when same is in contact with such riding surface independent of the means for actuating said carriage, and brake means provided by said propelling shoe when the actuating means therefore is held against movement.

2. A device of the character described comprising a sled body, a carriage disposed beneath said body arranged for reciprocal movement with relation thereto, foot pedals mounted on the front end of said sled, thrust rods connecting said carriage and said foot pedals, a propeller shoe mounted in said carriage and arranged for reciprocal movement with relation thereto, a hand actuating lever mounted in the body of said sled, a leverage means mounted on the underside of said body, leverage means connecting said hand lever and said leverage means, rods carried by said leverage means connecting with said propeller shoe, and means whereby when said foot pedals and hand lever are actuated said carriage causes said propeller shoe to contact the surface on which it rides and by actuating said hand lever propel said sled continuously in a forward direction.

3. A device of the character described comprising a sled body, a carriage disposed beneath said body arranged for reciprocal movement with relation thereto, foot pedals mounted on the front end of said sled, thrust rods connecting said carriage and said foot pedals, a propeller shoe mounted in said carriage and arranged for reciprocal movement with relation thereto, a hand actuating lever mounted in the body of said sled, a leverage means mounted on the underside of said body, leverage means connecting said hand lever and said leverage means, rods carried by said leverage means connecting with said propeller shoe; means whereby when said foot

pedals and hand levers are actuated said carriage causes said propeller shoe to contact the surface on which it rides and by actuating said hand lever propel said sled continuously in a forward direction, and means whereby when said foot pedals and hand levers are held against movement said propeller shoe acts as brake mechanism for said sled.

10 In testimony whereof I have affixed my signature.
